DESIGN FOR A PIN OR SIMILAR ARTICLE

Arthur Gerald Leary, Mount Vernon, N. Y.

Application May 6, 1944, Serial No. 113,498

Term of patent 3½ years

(Cl. D45—19)

To all whom it may concern:

Be it known that I, Arthur Gerald Leary, a subject of the King of Great Britain, and resident of Mount Vernon, in the county of Westchester and State of New York, have invented a new, original, and ornamental Design for a Pin or Similar Article, of which the following is a specification, reference being had to the accompanying drawing, forming a part thereof.

Fig. 1 is a top plan view of a pin or similar article embodying the design;

Fig. 2 is a side elevation of the pin or similar article shown in Fig. 1;

Fig. 3 is an end elevation of the pin or similar article looking from the left of Fig. 1; and

Fig. 4 is an end elevation of the pin or similar article looking from the right of Fig. 1.

The pin or similar article having the design shown is adapted to be associated, if desired, with any other suitable element or elements, as for attachment to a garment for personal wear.

I claim:

The ornamental design for a pin or similar article, substantially as shown and described.

ARTHUR GERALD LEARY.
